UNITED STATES PATENT OFFICE.

SAMUEL W. RUSHMORE, OF PLAINFIELD, NEW JERSEY.

STARTER FOR ENGINES.

1,405,742.

Specification of Letters Patent.

Patented Feb. 7, 1922.

Application filed December 20, 1919. Serial No. 346,431.

To all whom it may concern:

Be it known that I, SAMUEL W. RUSHMORE, a citizen of the United States, and resident of Plainfield, in the county of Union 5 and State of New Jersey, have invented certain new and useful Improvements in Starters for Engines, of which the following is a specification.

My present invention relates to devices of 10 the above type in which a motor driven pinion is shifted into driving engagement with a gear for rotating the crank shaft of the engine upon starting, and out of engagement after starting. It relates more 15 particularly to devices of the above type in which the pinion is shifted by screwing endwise along a screw element on the driving member, when one rotates faster than the other. Such differential rotation is due to 20 inertia effects upon sudden starting or stopping, either of the motor or the engine, and some auxiliary device such as an eccentric weight or friction drag is commonly employed to retard rotation of the pinion.

25 In starting devices of the above type employed on automobiles, the power for starting is commonly afforded by an electric motor operating on current derived from the storage battery. Such motors accelerate

30 with extreme rapidity the instant the circuit is closed. Consequently, the endwise screwing of the pinion either into or out of engagement with the engine gear is extremely rapid and the shock upon locking 35 of the gear to rotate with its shaft and the simultaneous taking up of the load is very great. A torque spring may be employed for moderating such shocks as set forth in another application of even date herewith.

40 Such spring when secured to a driving member at one end and to a driven member at the other end permits the driven member to lag behind the driver and thus yieldingly applies the power so as to moderate the 45 shocks.

Such torque springs, however, are noisy and frequently break and one object of my present invention is to secure similar results without the use of the torque spring.

50 My present invention contemplates the employment in this connection of friction driving means normally acting to apply to the pinion the maximum torque required for starting the engine but so arranged as to 55 afford a certain amount of slip at the in-

stant of excessive shock due to locking of the pinion and simultaneous taking up of the load, when it contacts with the stop which limits its endwise screwing movement.

An additional feature of my invention is 60 organizing the parts in such a way that the driving pinion itself will function mechanically through suitably related machine elements to automatically effect a slight release of the otherwise normally constant pressure 65 of the friction coupling, thereby permitting slip between the driving and driven members at the instant of abnormal power manifestation due to the momentum of the spinning shaft and armature. Preferably this 70 mechanism is so organized that after such momentary release the full normal pressure on the friction members is automatically restored so that the full power normally available in the motor will be applied for driving 75 the engine at the speed required for starting.

The above and other features of my invention may be more fully understood from the following description in connection with the accompanying drawings, in which— 80

Figure 1 is a schematic view partly in section showing the organization of parts according to one desirable embodiment of my invention; and

Figure 2 is a detailed view on a somewhat 85 larger scale showing a modification.

In these drawings the crank shaft C of the internal combustion engine is provided with fly-wheel F having gear G formed on the periphery thereof. In operative relation 90 thereto are the electric starting motor 1, having an armature shaft 2 carrying a screw-threaded sleeve 3, carrying an internally threaded pinion 4 provided with gear teeth 5. The motor shaft is parallel with the 95 crank shaft so that screwing of the pinion endwise along the sleeve sets it into and out of mesh with the gear teeth on the fly wheel. Inward movement of the pinion is limited by a collar 6 preferably integral with the armature shaft 2. Any desired means may be employed for retarding rotation of the pinion when the starting of the engine operates to drive the pinion faster than the motor shaft, as, for instance, the friction spring 8. 100

Any suitable means may be employed for closing the circuit of the motor as for instance, the switch S connected in series with battery B.

The means for frictionally applying the 110

desired torque from the drive shaft 2 to the sleeve consist of the friction disc 9 integral with sleeve 3 and the cooperating annulus 10 carried by the box like structure 11 which 5 is rigidly secured to the shaft 2 through bolts 12 and disc 13 which is secured to the shaft 2 by set screw 14.

The friction disc 9 is forced into frictional engagement with the annulus 10 by means 10 of spring 15. The area of the frictional surface and the stiffness of spring 15 are predetermined with a view to transmitting from shaft 2 to pinion 4 the maximum torque required for rotating gear wheel G 15 up to the starting speed.

It will be noted that spring 15 is not secured either to the driving or driven member and serves none of the functions of a torque spring; also the sleeve 3 is secured 20 to the shaft only by pressure of said spring 15 forcing disc 9 into contact with annulus 10. Hence, said sleeve can be shifted endwise to the left to relieve the friction if sufficient power be applied to compress the 25 spring 15. Moreover, said sleeve may slip and rotate at slower speed or even remain stationary while shaft 2 is rotating whenever sufficient power is applied to overcome the normal friction or when said friction is reduced or eliminated by the above described 30 endwise movement of the sleeve to the left in opposition to the pressure of spring 15.

From the above description of the parts the operation of the device will be readily 35 understood. When the switch S is closed the armature shaft 2 with its integral collar 6 and carrying with it the sleeve 3 will be rotated. Rotation of the pinion 4 will be prevented or at least retarded by inertia.

40 Hence the pinion will screw endwise into mesh with gear G. The starting speed of the motor being very great and practically unimpeded up to the moment when the gear 4 butts against collar 6 and the pinion 4 being then practically stationary and in mesh with stationary fly-wheel gear G, there is an instant when the momentum stored up in the rapidly rotating armature and shaft apply an abnormally excessive torque.

45 With the arrangement shown in the drawings, the effect of this is to tend to screw the pinion still farther to the right but as the pinion cannot screw farther toward the right because it is already butting against 50 collar 6, the tendency is to screw the sleeve in the opposite direction thus tending to relieve the frictional pressure of disc 9 on annulus 10. This permits the pinion and sleeve to lag behind the drive shaft during the

55 time needed to take up the shock and start the fly-wheel of the engine. The pressure of spring 15 being constant, will operate automatically to restore disc 10 to full frictional engagement with annulus 9 as soon as

the abnormal or shock conditions have been 6 equalized by getting the fly-wheel of the engine in motion and corresponding slowing down of the motor armature.

It will be understood that the above described endwise movements of the sleeve are 70 likely to be minute and in many cases will manifest themselves merely as decrease of pressure of the frictional surfaces rather than as observable movements of the sleeve.

It will be evident also that if the pressure 75 of spring 15 be properly gauged so as to afford a closely regulated pressure slightly greater than the maximum normal torque, the friction surfaces may slip sufficient to take up the shock without any endwise movement of the sleeve 80 3.

In the embodiment of my invention shown in Figure 2, the number and nature of the essential elements is the same but the organization of the parts is different in detail. In 85 this figure, the fly-wheel G, pinion 4, spring 8, screw sleeve 3 with friction disc 10 may be the same as before. The pinion 4, however, when screwed to the end of the sleeve, comes into contact with collar 16 rigidly secured 90 on sleeve 3 by set screws 4^a. Hence, screwing the pinion 4 until it butts against the collar cannot have any tendency to screw the sleeve 3 to the left. An equivalent function is performed in a better and more easily determinable manner by the cooperating friction disc 19 which is internally screw-threaded as at 95 20 so as to fit the multiple thread steep pitch screw 21 cut in the outer portion of the armature shaft 2. This friction disc 19 is forced 100 endwise into frictional engagement with disc 10 by stiff thrust spring 25. This spring like spring 15 previously described is not a torque spring but operates merely by its endwise thrust to force disc 19 against disc 10 105 with the pressure required to transmit the normal maximum torque required for starting the engine.

The operation of this form of my invention is similar to that of Figure 1 except that 110 in Figure 2, it is the disc 19 that screws rearwardly to relieve the friction pressure at the instant of maximum shock, the pinion and sleeve being at this instant relatively locked by reason of the stress forcing pinion 4 into contact with the collar 16 which, as before stated, is rigid with the sleeve 3, and thus prohibits further relative movement of sleeve and pinion until the direction of rotary stress is reversed by the starting of the engine and consequent driving the pinion at a speed overrunning the speed of the armature shaft.

One functional advantage of the arrangement shown in Figure 2 over that shown in 115 Figure 1 is that the endwise movement for 120 relieving the pressure and friction of the friction members is predetermined by the

pitch of the thread 21 which may be designed solely for this function, whereas in Figure 1 the endwise shift and friction release is dependent upon the pitch of the thread on sleeve 3 which must be predetermined with reference to satisfactory endwise screwing of gear 4 into and out of mesh with flywheel G.

I claim:

10. 1. In an engine starter of the type including an electric starting motor, a shaft driven thereby, a screw element rotated by said shaft, a pinion adapted to screw endwise into and out of engagement with a gear for 15 starting the engine according as said screw element rotates faster or slower than said pinion, and, in combination with said parts, a friction coupling interposed between the electric starting motor and the engine, said 20 coupling having frictional engagement sufficient to transmit the normal power required for driving the engine up to starting speed, but insufficient to withstand the abnormal torque developed by the momentum of the 25 driving members acquired during the shifting of said pinion, together with means whereby abnormal torque, applying abnormal endwise screwing effort, operates automatically to reduce the pressure of the friction elements of said friction coupling.

2. The combination specified by claim 1 in which a spring is arranged as the means to

oppose reduction of the pressure of the frictional elements.

3. The combination specified by claim 1, in 35 which the screw element is formed on a sleeve free for rotary and longitudinal movement on the armature shaft and formed with a friction surface as one element of said friction coupling, the cooperating friction surface being mounted upon and being driven by the armature shaft, said parts being located and relatively arranged so that the abnormal torque will cause endwise screwing of one of said friction elements in a direction 45 to relieve the pressure on their frictional surfaces.

4. The combination specified by claim 3, in which a spring is arranged as the means to oppose reduction of the pressure of the frictional elements. 50

5. The combination specified by claim 3, in which the shaft-driven frictional element is screw threaded to the drive shaft, by a screw of opposite twist to that of the sleeve screw, 55 and in which a thrust spring is employed as the means for preventing unscrewing of said shaft engaging friction element under normal torque but is adapted to yield and permit such movement under abnormal torque. 60

Signed at New York city in the county of New York, and State of New York, this 13th day of December, A. D. 1919.

SAMUEL W. RUSHMORE.
